[57] **CLAIM**

The ornamental design for a deflector for swimming pool skimmer, as shown.

DESCRIPTION

FIG. 1 is a top plan view of a deflector for swimming pool skimmer, showing my new design;

FIG. 2 is a front elevational view.

FIG. 3 is a bottom plan view.

FIG. 4 is a rear elevational view.

FIG. 5 is a right side elevational view, the left side elevational view being a mirror image thereof.
